Morris A. Heimann,

By Hugh K. Wagner,
Attorney

UNITED STATES PATENT OFFICE.

MORRIS A. HEIMANN, OF ST. LOUIS, MISSOURI.

GARMENT HANGER.

Application filed May 7, 1923. Serial No. 637,263.

To all whom it may concern:

Be it known that I, MORRIS A. HEIMANN, a citizen of the United States, residing at the city of St. Louis, in the State of Missouri, have invented certain new and useful Improvements in Garment Hangers, of which the following is a specification.

This invention pertains to clothes-hangers, and more particularly to an improved form 10 of garment hanger of the type having a support which is inserted into the inside of the garment and on which the shoulders of the garment rest.

In placing loose-neck or wide-neck gowns 15 on this type of hanger, it often occurs, especially if the hanger becomes tilted to one side, that the garment slides along the support until the neck-band reaches one end thereof, whereupon the garment falls away 20 from that end of the support, and the support becomes tilted in the opposite direction, with the result that the garment falls from the hanger entirely. The purpose of this invention is to provide means for curing this 25 defect in the hanger.

In the accompanying drawings forming part of this specification, in which like numbers of reference denote like parts wherever they occur,

0 Figure 1 is a plan view of the hanger with a section through the supporting hook on the line 1—1 of Figure 3;

Figure 2 is a section on the line 2—2 of Figure 3; and

35 Figure 3 is an elevation of the complete hanger, with the outline of a garment shown in dotted lines.

Referring to the drawings, a curved rod 1, preferably wood, is provided in the middle 40 with a wire supporting-hook 2. So far this constitutes a conventional type of hanger.

This invention resides in placing on the hanger an obstruction which will prevent the sliding of the garment along the length of 45 the hanger. For this purpose a straight length of wire 3 is bent one complete turn 4 in the middle and bent at 5 near each of its ends 6 to an acute angle 7, the end bends 5 being at right angles to the middle bend 4, and the end bent-portions 8 converging to

ward one another. The ends 6 are flattened to a wedge shape, the edges 9 of both wedges lying in one plane.

The wire obstruction thus formed is placed with its bend or loop 4 around the end 10 of the hook 2 and with its end portions 8 on top, as shown in dotted lines in Figure 3. It is then moved up the straight end portion 11 of the hook and around the curve 12 and then down the straight portion 13 as far as it will 55 go, with the wedge edges 9 resting on the top of the curved rod 1. A sharp blow is then struck with a hammer against the bends 5 in the direction of the end portions 8, thereby driving the wedges 6 into the rod 1, and 60 forming the complete hanger.

In use, the garment 14 is slipped over the hanger, the wire 3 projecting through the neck-opening 15 of the garment 14 and preventing the garment from sliding off the 70 curved rod 1 by the contact of its obstructing end portions 8 with the garment neck-band or neck-opening margin 16.

It is to be noted that with this construction there are no sharp points or projections 75 to catch and tear the garment, and furthermore, the bracing effect due to the end portions 8 being parts of one unit and, also, being connected to the hook 2 results in greater rigidity and ruggedness of construction than if the end portions 8 were entirely separate units.

Having thus described this invention, I hereby reserve the benefit of all changes in form, arrangement, order, or use of parts, as 80 it is evident that many minor changes may be made therein without departing from the spirit of this invention or the scope of the following claims.

I claim:

1. A garment hanger comprising a curved rod having a supporting hook, and a garment-retaining member consisting of a relatively straight bar having an eye through which the shank of the said hook is adapted to extend, and having, also, end bent-portions converging toward one another and anchored at their lower ends to the said curved rod, the said end bent-portions being adapted to project through the neck open- 90 95 100

ing of a garment placed on the hanger and preventing the garment from sliding off the curved rod.

2. In a garment hanger, a member for preventing a garment from sliding off the hanger, which member consists of a straight length of wire bent one complete turn to provide a central eye for engagement over the

hook of the hanger and having end bent-portions converging toward one another and terminating in ends flattened to a wedge shape so as to be adapted to be forceably driven into the rod of the hanger. 10

In testimony whereof I hereunto affix my signature.

MORRIS A. HEIMANN.
